UNITED STATES PATENT OFFICE.

CARTER F. BUSSE, OF CHAMOIS, MISSOURI.

CONCRETE CEMENT POST.

1,006,718.

Specification of Letters Patent.

Patented Oct. 24, 1911.

Application filed March 19, 1910. Serial No. 550,450.

To all whom it may concern:

Be it known that I, CARTER F. BUSSE, a citizen of the United States, residing at Chamois, in the county of Osage and State of Missouri, have invented certain new and useful Improvements in Concrete Cement Posts, of which the following is a specification.

This invention relates to improvements in concrete cement posts and embraces the construction of a post having reinforcing bars extending longitudinally thereof and embedded in the material of the post.

One of the objects of the invention is the production of a post which is adapted to be made quickly and cheaply and provided with a plurality of reinforcing bars extending longitudinally thereof and connected at the ends of the post, so as to form effective tie bars and holds for the wires of a fence.

With the above and other objects in view the invention comprises certain combinations, constructions and arrangements of parts, clearly described in the following specification and clearly illustrated in the accompanying drawings, in which—

Figure 1 is a side elevation of the improved post, Fig. 2 is a cross section on the line 2—2 of Fig. 1, Fig. 3 is a transverse sectional view showing a modified form of spacing member, Fig. 4 is an elevation showing a plurality of bars, and Figs. 5, 6, and 7, are sections showing spacing members, on the lines 5—5, 6—6 and 7—7 respectively of Fig. 4.

Referring to the accompanying drawings illustrating the invention 1 denotes the concrete or cement body of the post, which is formed with a base portion 2, tapering inwardly to the lower end thereof and a post portion proper, 3, which tapers inwardly to the upper end.

The body 1 is formed of any shape and may have concave or convex sides or surfaces, as desired. Near the upper end of the body 1 and between the upper and lower ends thereof members 4, are embedded, which are provided for the purpose of holding the longitudinally extending tie bars spaced apart and for giving said bars a good connection when the post is being molded or formed.

The members 4 are formed of a shape corresponding to the shape of the post and a number of said members may be embedded between the ends of the post at spaced points and of different sizes.

Tie bars 6 are embedded in the body 1, extending from one end to the other end and passed over or through the members 4.

The spacing members 4 may be all shaped triangular or only one so shaped. The tie rods 6 extend through said members to connect with the base 7, which is formed triangular. A central tie bar 8 extends through the members 4 and the post.

Having described my invention I claim and desire to secure by Letters Patent:—

As an improved article of manufacture, a collapsible skeleton for reinforcing concrete posts, comprising a plurality of triangular, tapering spacing members, adapted to support and space apart a centrally disposed tie rod, and a tie rod in each of their triangular extremities and a triangular base adapted to support the said tie rods in adjusted position.

In testimony whereof I affix my signature in presence of two witnesses.

CARTER F. BUSSE.
